(57) **CLAIM**

The ornamental design for a burner assembly with integrated heat shield, as shown and described.

DESCRIPTION

FIG. 1 is a perspective view of a burner assembly with integrated heat shield, showing our new design;

FIG. 2 is a front perspective view of a burner assembly with integrated heat shield, showing our new design;

FIG. 3 is rear perspective view of a burner assembly with integrated heat shield, showing our new design; and,

FIG. 4 is top perspective view of a burner assembly with integrated heat shield, showing our new design.

The broken line showing of the burner assembly illustrates the environment of the claimed design and forms no part thereof.
